UNITED STATES PATENT OFFICE.

CHARLES M. DREYER, OF ST. LOUIS, ASSIGNOR, BY DIRECT AND MESNE ASSIGNMENTS, TO MARTHA J. MARSDEN, OF BRIDGETON, AND JAMES G. GRACEY, OF ST. LOUIS, MISSOURI.

PISTON-LUBRICATOR.

SPECIFICATION forming part of Letters Patent No. 471,068, dated March 15, 1892.

Application filed September 14, 1891. Serial No. 405,635. (No model.)

To all whom it may concern:

Be it known that I, CHARLES M. DREYER, of St. Louis, Missouri, have made a new and useful Improvement in Lubricators, of which 5 the following is a full, clear, and exact description.

The present invention, when fully carried out, comprises an oil or grease cup attached to a hydraulic cylinder and having means 10 whereby its contents are injected into the cylinder to oil the same at each stroke of the cylinder-piston, said piston in its movement actuating mechanism for opening and closing the passage leading from said cup to the cylinder, 15 substantially as is hereinafter described and claimed, aided by the annexed drawings, making part of this specification and exhibiting the most desirable mode of carrying out the improvement, and in which—

20 Figure 1 is a longitudinal sectional elevation exhibiting the improved mechanism, and also a sufficient portion of a hydraulic cylinder for an understanding of the working of the improvement, the parts being arranged 25 as before the piston has been moved into the position for actuating the valvular mechanism of the grease-cup; Fig. 2, a similar view, the piston being moved out to encounter but not to operate the valvular mechanism; Fig. 30 3, a similar view, the piston having completed its stroke and the passage for supplying the grease to the cylinder being open; and Fig. 4, an end elevation of the parts, the view being in the direction of the arrow of Fig. 3.

35 The same letters of reference denote the same parts.

The cylinder A is of the usual construction, saving as it is modified or supplemented by the improvement under consideration. B represents any vessel or cup suitable for containing the lubricating material C. If said material is sufficiently fluid, it will when the passage is open flow into the cylinder; but as in many instances it is desirable to use grease 40 for the lubricating material, or some form of lubricating material which requires an application of force to effect its delivery into the cylinder, provision is made for producing the

downward pressure upon the contents of the cup.

G represents a piston, which, by reason of its weight and the spring g, presses downward upon the material C with sufficient force to cause said material to flow readily into the cylinder when the passage-pipe E, leading 50 from the cup to the cylinder, is opened. By means of a valve F the passage E may be opened or closed or partly opened, as may be desired. The cylinder is suitably perforated at a to complete the passage-pipe E. When 55 the cylinder is to be lubricated, the valve F is suitably opened to permit of the passage of the lubricating material. The introduction of the lubricating material into the cylinder, however, is at intervals—namely, at each 60 stroke of the cylinder-piston D—and to this end another valve H is employed. This last-named valve is inserted in the passage-pipe E, substantially as shown, and the motion of the piston is communicated to its stem h to 65 open the valve, preferably in the following manner: The piston is provided with a projection, which is preferably in the form of a roller I, journaled in arm i, which is suitably attached to the piston. A lever J is pivoted 70 at j to a bracket K, which, by means of the bolt k, is fastened to the cylinder. The lower end j' of said lever extends into the field of the movement of the piston projection. The upper end j'' of this lever, by means of the rod L, 75 is jointed to the handle h' of the valve-stem h. The action of the parts is illustrated in Figs. 1, 2, and 3. In Fig. 1 the piston is withdrawn into the cylinder and the valve H is closed. In Fig. 2 the piston has moved outward and its projection I has encountered the lever J. At this point in the stroke of the piston the device preferably employed for 80 distributing the lubricating material is nearly in position for receiving the lubricant. This device is attached to the piston upon the outer side thereof, moving to and fro with the same, and consisting as follows: M represents a ring composed, say, of copper, which, by means of the bolts d, is attached to the piston. The ring is projected first horizontally 85

from the piston and then radially outward at 5
m' to meet or come quite near to the internal
surface of the cylinder and thereby to inclose
a space N in front of the piston and next to
the inner surface of the cylinder suited to re- 10
ceive and carry the lubricant delivered from
the passage-pipe E. A part O, composed,
preferably, of a piece of rubber tubing and
serving partly as a packing and partly as a
lubricant-distributer, is secured to the ring M,
within its flange m'. In the position of the piston
in Fig. 2 said part O is opposite the outlet
from the passage-pipe E and the piston has not
yet completed its stroke and the valve H is still
closed. In Fig. 3 the piston has moved outward
to the end of its stroke. Its motion, by means of
the parts I, J, and L, has been communicated
to the stem h, and the valve H has been thereby
opened and the lubricant has been injected
into the space N. The piston now makes its
return stroke, and as the piston projection I
withdraws from the lever J a weight P upon
an arm j³ of the lever J acts to turn said arm
and lever again into the position of Figs. 1
and 2, thereby closing the valve H, and said
valve H and the described parts for operating
it remain in that position until the piston is
again moved outward, when the operation is
repeated. The packing O is held in place, as
shown, by any suitable means, such as the
rivets o, which pass through the ring M into
the packing.

I claim—

1. In a piston-lubricator, the combination
35 of the cylinder, the piston D, working therein
and having an arm i, the lever J in front of
the cylinder, and the oil-pipe E, and valve H,

and mechanism connecting the lever J with
said valve H, substantially as and for the
purposes set forth. 40

2. In a piston-lubricator, the combination
of the cylinder having thereon the ring M, in-
closing the space N in front of the piston,
and the packing and lubricant-distributer O,
secured to the ring, the arm i, and the oil-pipe 45
having valve H, and mechanism for automatically
opening and closing same, substantially
as described.

3. In a piston-lubricator, the combination
of the cylinder and the piston, as described,
operating in it and having an arm i, the pipe
E, communicating with the interior of the
cylinder at a, and the weighted lever J, piv- 50
oted to the bracket K, the rod L, and the valve
H in said pipe, the said rod connected with
and adapted to operate said valve, all sub-
stantially as described.

4. In a piston-lubricator, the combination
of the cylinder carrying an automatic force-
feed reservoir, as set forth, and a piston op- 60
erating in it and provided with arm i, of the
pipe E, communicating with the interior of
the cylinder at a, the weighted lever J, piv-
oted to the bracket K, the rod L, and the valve
H in said pipe E, said rod L being connected 65
with and adapted to operate said valve, sub-
stantially as shown and described.

Witness my hand this 5th day of September, 1891.

CHARLES M. DREYER.
